UNITED STATES PATENT OFFICE.

CLOVER AMRINE, OF VERMONT, ILLINOIS.

PARCEL-CARRIER.

SPECIFICATION forming part of Letters Patent No. 593,171, dated November 2, 1897.

Application filed July 27, 1896. Serial No. 600,732. (No model.)

To all whom it may concern:

Be it known that I, CLOVER AMRINE, a citizen of the United States, residing at Vermont, in the county of Fulton and State of Illinois, have invented certain new and useful Improvements in Parcel-Carriers; and I do hereby declare that the following is a full, clear, and exact description of the invention, which will enable others skilled in the art to which it appertains to make and use the same.

My invention relates to certain new and useful improvements in parcel-carriers by means of which a simple device is provided for that purpose.

More particularly my invention relates to a parcel-carrier of the class that is commonly used for carrying shawls and other small parcels, and is particularly well adapted to be used by school children for carrying books, slate-pencils, lead-pencils, and other of the necessary paraphernalia used by children in school work.

My invention consists, essentially, of a hollow tube closed at one end and open at the other end and provided with a cap for closing the open end of the tube, extensions from the tube and secured thereto provided with central openings, a clasp secured to the lower portion of the respective extensions from the tubes, through which a strap is passed and held in such a manner as to permit the moving of the strap back and forth in the said clasp, and other minor details of construction, hereinafter more particularly mentioned.

That my invention may be more fully understood, reference is had to the accompanying drawings, in which—

Figure 1 is a vertical section lengthwise through the device. Fig. 2 is a cross-section 40 through the same.

In the figures, A is a hollow tube, which is preferably made of tin or other sheet metal, but may be made of wood or any other suitable material. This tube may be covered 45 with leather or any other suitable material, as may be desired.

A' is a cap purposed to be fitted over the open end of the tube, as shown in the drawings. B and B' are extensions from the main

tube, provided with the central openings, as 50 shown. These pieces are secured to the tube by means of the clasp a, which bears over the upper ends of the extensions and is soldered, together with the extensions, to the tube. Of course it will be understood that other means 55 may be provided for securing the extensions to the tube, and other forms of extensions may also be used, if desired. The extensions B and B' are separated at their lower extremities a short distance and are connected and 60 braced by means of the plate C, which bends around the lower parts of the extensions, as at c c, the lower portions of these said extensions being designated in the drawings by the letters b b. c' c' are the edges of the 65 plate, bent over to form clips purposed to retain the strap D.

In applying the device to practical use the straps may be caused to engage the parcels being carried, and when used by school children the said straps will hold the books and pencils, and other small articles may be placed in the interior of the tube A.

The advantage of the use of the extensions B is that when the parcel-carrier is not used 75 the straps may be passed through the central openings repeatedly until the space is filled, when the upper edge of the extensions or the plate holding them will impinge the end of the strap and maintain the same in a rolled-up condition. It also has the further use that when holding a flat parcel, as books, it leaves 80 a space between the handle or tube and the parcel for convenience in carrying.

Having thus fully described my invention, 85 what I claim, and desire to secure by Letters Patent, is—

1. In a combined parcel-carrier and scholar's companion, the combination with the hollow handle A provided with the cap A' at one 90 end, of the extensions B, B' secured thereto provided with central openings, the plate C, formed with clips c' purposed to retain a strap and permit of its moving back and forth therein, all substantially as described and 95 shown.

2. In a combined parcel-carrier and scholar's companion, the combination with the hol-

low handle A having a cap A' at one end, and the extensions B, B' provided with central openings and secured to the handle by means of the clasps a, of the plate C connecting and securing together their lower extremities, the said plate provided with clips c' through which a strap is passed and held in such a manner as to permit the moving of the strap

back and forth therein, all substantially as described and shown. 10

In testimony whereof I affix my signature in presence of two witnesses.

CLOVER AMRINE.
